CONTROL PANEL FOR AN ELECTRONIC INVENTORY CONTROL SYSTEM

John Gault, Marlton, N.J., assignor to Video
Systems Corp., Pennsauken, N.J.

Filed Nov. 28, 1973, Ser. No. 419,553

Term of patent 14 years

Int. Cl. D13—03

U.S. Cl. D26—13 C

FIG. 1 is a front view of a control panel for an electronic inventory control system in accordance with the present invention;

FIG. 2 is a rear view thereof;

FIG. 3 is a top plan view thereof;

FIG. 4 is a bottom plan view thereof;

FIG. 5 is a right side elevation view thereof; and

FIG. 6 is a left side elevation view thereof.

I claim:

The ornamental design for a control panel for an electronic inventory control system, substantially as shown and described.
